UNITED STATES PATENT OFFICE.

HOWARD L. COBURN, OF BOSTON, MASSACHUSETTS.

REINFORCED CONCRETE DAM.

No. 845,855.

Specification of Letters Patent.

Patented March 5, 1907.

Application filed May 2, 1906; Serial No. 314,847.

To all whom it may concern:

Be it known that I, HOWARD L. COBURN, of Boston, in the county of Suffolk and State of Massachusetts, have invented certain new and useful Improvements in Reinforced Concrete Dams, of which the following is a specification.

This invention relates to a dam comprising a body structure of concrete; and it has for its object to enable a concrete dam to be built originally to a minimum height and left in such condition that while it is practically operative as a dam its height can be readily increased by adding to the original concrete structure without altering any of the permanent parts thereof.

To this end the invention consists in the improvements which I will now proceed to describe and claim.

20 Of the accompanying drawings, forming a part of this specification, Figure 1 represents a cross-section of a dam of minimum height constructed in accordance with my invention and adapted to be built upon or extended upwardly to form a higher dam. Fig. 2 represents a view similar to Fig. 1, showing the dam completed by additions to the structure shown in Fig. 1. Fig. 3 represents a side or face view of the dam shown 25 in Fig. 2 looking from the downstream side of the dam. Fig. 4 represents a view of a modification.

The same reference characters indicate the same parts in all the figures.

35 Referring to Fig. 2, *a* represents the deck, and *b* the apron, of a reinforced concrete dam, the said parts being connected by the crest *c* and provided with reinforcing rods or members *d*, embedded in the concrete and suitably arranged to impart the desired strength thereto. The deck, crest, and apron are here shown as forming an approximately roof-shaped structure, the deck and apron being arranged at different angles, as shown. 40 The space under the deck, apron, and crest is subdivided by buttresses extending crosswise of the space covered by the deck, crest, and apron, the said buttresses being also composed of concrete.

45 In carrying out my invention, I construct a relatively low dam, which comprises the lower part of the deck and corresponding portions of the buttresses *e*, as shown in Fig. 1, the upper portion of the deck, the crest, the apron, and the upper portion of the buttresses shown in Fig. 2 being omitted. The

deck and buttresses thus formed are supplemented by a temporary apron structure *s*, which may be composed of planking secured to beams or stringers *f*, suitably affixed to the 50 buttresses. The upper edge of the deck is preferably provided with a lip or flange *g*, which constitutes the crest. The buttresses are provided with tie-rods *h*, which are embedded in the concrete bodies of the buttresses and project therefrom to a sufficient extent to enable them to be anchored firmly in the concrete which is subsequently added to extend the buttresses, as shown in Fig. 2. The buttresses are preferably formed with angular or serrated edges, the faces of which constitute seats to engage buttress extensions *e'*, subsequently applied, the rods *h* projecting from said seats, although, if desired, the buttresses as originally formed may have seats 75 which are inclined or otherwise formed, the rods *h* projecting from said seats, as shown in Fig. 4.

The arrangement of the extension-engaging seats or edges of the buttresses is such 80 that the projecting portions of the tie-rods are protected by the planking forming the temporary apron *s*. The apron-supporting beams or stringers *f* are preferably secured to the buttresses by means of bolts *i*, embedded 85 in the buttresses and projecting through the faces on which the beams *f* are seated.

The structure shown in Fig. 1 is a substantial and operative dam and is at the same time adapted to be built upon by reinforced 90 concrete construction and raised and provided with a concrete apron, as shown in Fig.

2. Prior to the raising of the dam the temporary apron *s* and the supporting-beams *f* will be removed, thus exposing the projecting 95 portions of the tie-rods *h*. Concrete extensions may now be added to the buttresses and to the deck to raise the dam, the concrete added to the buttresses being firmly anchored to the original portions of the buttresses by 100 the rods *h*.

I claim—

1. A concrete-dam structure having seats adapted to support a concrete-dam extension, projecting members adapted to enter 105 said extension, and a temporary structure forming a part of the dam and protecting the said projecting members, the said temporary structure being detachable from the concrete structure.

2. A concrete dam comprising a deck, buttresses supporting the deck, the deck and

- 2
- buttresses having seats adapted to support concrete extensions, and extension-engaging members projecting from the seats on the buttresses. 30
- 5 3. A concrete dam comprising a deck, buttresses supporting the deck, the said deck and buttresses having seats adapted to engage concrete extensions, and a temporary apron detachably secured to the buttresses 35 and covering the seats thereon.
- 10 4. A concrete dam comprising a deck, buttresses supporting the deck and provided with seats adapted to engage concrete-but- 40 tress extensions, and tie-rods embedded in the buttresses and projecting from said seats to enter the buttress extensions.
- 15 5. A concrete dam comprising a deck, buttresses supporting the deck and provided with seats adapted to engage concrete-but- 45 tress extensions, tie-rods embedded in the buttresses and projecting therefrom to enter the said buttress extensions, and a temporary apron detachably secured to the buttresses and covering the projecting rods.
- 20 25 6. A concrete dam comprising a deck, but- 40 tresses supporting the deck, and provided with alternating projections and recesses, the sides of which constitute seats adapted to engage concrete-butress extensions, and tie-rods embedded in the buttresses and projecting from said seats to enter the said exten- 30 sions.
7. A concrete dam comprising a deck, but- 35 tresses supporting the deck, and provided with buttress-extension seats and with apron-seats, bolts embedded in the buttresses and projecting from the apron-seats, and a temporary apron having supporting-beams en- gaged with said bolts.
8. A concrete dam comprising a deck hav- 40 ing at its upper edge a lip or flange forming a seat for a deck extension, buttresses supporting the deck and having buttress-extension seats and temporary apron-seats, and a tem- 45 porary apron supported by said apron-seats and inclined downwardly from the said deck-extension seat.
- In testimony whereof I have affixed my signature in presence of two witnesses.
- HOWARD L. COBURN.
